UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

CAR CONSTRUCTION.

Application filed September 26, 1923. Serial No. 664,869.

This invention relates to improvements in car construction.

The object of the invention is to provide a simple, efficient and inexpensive means, especially adapted for mine cars, for effectively cushioning shocks under buff and draft, and wherein provision is made for coupling the cars in the usual simple manner.

10 In the drawings forming a part of this specification, Figure 1 is a vertical, longitudinal, sectional view taken through the end portions of two adjacent mine cars, showing my improvements in connection therewith. Figure 2 is a partial, horizontal, sectional view and partial top plan view of the construction shown in Figure 1. Figure 3 is a transverse, vertical, sectional view corresponding substantially to the line 3—3 15 of Figure 2. Figure 4 is a vertical, longitudinal, sectional view taken through one end of a mine car, illustrating a different embodiment of the invention. And Figure 20 5 is a view similar to Figure 2 further illustrating the embodiment of the invention shown in Figure 4.

In said drawings, referring first to the embodiment of the invention illustrated in Figures 1 to 3 inclusive, each mine car is 30 shown as provided with a suitable heavy flooring 10, a vertical end wall 11 at one end, and a horizontally pivoted gate 111 at the other end, the gate end of one car being disposed adjacent the closed end of 35 the next car as shown in the drawings.

In carrying out my invention, I employ a draw bar 12 extending full length of the car and an auxiliary draw bar 13 at one end of each car, the draw bar 12 being in the 40 form of a horizontally disposed plate secured to the upper surface of the flooring 10 and the auxiliary bar 13 being in the form of a horizontally disposed plate secured to the under surface of the flooring. 45 10. At the closed end of the car, the bars 12 and 13 are secured in fixed position, preferably by bolts 14 and 15 passing through the respective bars and flooring, a plurality of bolts similar to the bolts 14 50 being provided at spaced intervals through the length of the drawbar. The flooring 10, at the closed end of each car, is cut away as indicated at 16 to provide a recess adapted to accommodate the shock absorbing mech-

anism hereinafter described, and the corresponding end of the drawbar 12 and the auxiliary drawbar 13 extend outwardly beyond the end of the cut away portion of the flooring as clearly shown in Figures 1 and 2, the drawbar 12 passing through the end wall 11. The outer end portion of the auxiliary drawbar 13 is offset downwardly as indicated at 17 to accommodate a reinforcing bar 18 extending transversely of the car and abutting the under surface of the flooring. At their outer ends, at the closed end of the car, the bars 12 and 13 are provided with aligned, longitudinally extending slots 19—19, adapted to receive a vertically disposed bolt 20 for sliding movement in a direction longitudinally of the car. The bolt 20 serves as a means for connecting the shock absorbing mechanism, hereinafter described, to the car.

The shock absorbing mechanism proper, located at the closed end of the car, as shown, preferably comprises two members A and B and two pairs of springs C—C interposed therebetween. The member A is in the form of a vertically disposed, transversely extending, relatively heavy plate having a central extension 21 at the front end thereof, upper and lower flanges 22 and 23 merging with the upper and lower faces of the extension 21, and side webs 24 connecting the flanges. A pair of pockets 25 are thus provided adapted to receive the inner ends of the springs C—C. The extension 21 works between the bars 12 and 13 and is slotted as indicated at 26 to accommodate the bolt 20.

The member A functions as a rear follower and is adapted to be coupled to the adjacent car by a chain 27 or any other suitable flexible connecting means. The chain 27 is preferably connected to the follower A by a shackle 28 pivotally connected to the extension 21 by means of a horizontally disposed pin 29.

The member B is preferably in the form 100 of a hollow casting having spaced top and bottom walls 30 and 31 and a front wall 32. The front wall 32 and the bottom wall are cut away as indicated at 33 to accommodate the shackle 28 for swinging movement, and the front and bottom walls are reinforced adjacent the cut away portion by vertical webs 34. The top and bottom walls

30 and 31 straddle the member A and the draw-bar 12 is also provided with the usual bars 12 and 13, and are perforated to accommodate the bolt 20. The bolt 20 is provided at its lower end with a nut 35 by which it is retained in position, a cotter pin being preferably provided to prevent accidental removal of the nut. Additional means is preferably provided to properly guide the sliding movement of the member B and prevent damaging and distortion of the springs C-C when the member B is struck from one side, as for instance, when the cars are on a curved track. This means comprises a pair of bolts 36 fixed to the member A at opposite sides thereof and each working in a pair of aligned slots 37 formed in the upper and lower walls of the member B, the upper and lower flanges 22 and 23 of the member A being perforated to accommodate the bolts 36. The bolts 36 are retained in position by nuts at the lower ends thereof, the nuts being so adjusted as to permit free relative sliding movement of the members A and B. Washers are preferably interposed between the upper and lower faces of the member B and the head and nut of each bolt, respectively. The bolts 36 may also be provided with cotter pins to prevent accidental removal of the nuts.

The pair of springs C-C is interposed between the members A and B and the same are located at opposite sides of the extension 21. Each spring C comprises an outer relatively heavy coil and an inner relatively lighter coil, and the same are held in properly centered position by lugs 137 on the plate A and the front wall 32 of the member B, respectively, said lugs extending into the inner coil of each pair. When mechanism is in normal assembled position, as in Fig. 2, springs C-C are preferably held under a certain amount of initial compression by means of the bolts 26 and 36, which serve to limit the relative separation of the members A and B.

The member B functions as a front follower and buffing plate, and the outer face of the front wall 32 thereof is rounded off at its opposite ends for a purpose herein-after described.

At the gate end of each car the draw-bar 12 extends through the end gate 111 and is secured to the flooring 10 by a bolt 39 extending through the flooring 10, auxiliary buffing block 40 and a transversely extending car-body reinforcing bar 41. The flooring 10 at the gate end of the car is cut away as indicated at 42 to provide a recess to accommodate the coupling chain 27. The drawbar 12 at the gate end of the car, is provided with a downwardly extending flange 38 adapted to abut the inner wall of the recess and serving to relieve the bolts 14 from some of the pulling-stresses. The

draw-bar 12 is also provided with the usual perforation as indicated at 43 adapted to receive the hook 44 at the adjacent end of the coupling chain 27.

The gate end of each car is also provided with a pair of buffing plates 45, located on opposite sides of the center line of the car and adapted to co-operate with the member B at the opposite end of the adjacent car. Each of the buffing plates 45 is in the form of a hollow casting or pressed plate telescoped over the projecting end portion of the flooring 10 and reinforcing member 40, at one side of the recess 42. The outer face of each buffing plate is slightly rounded as indicated at 46 so as to properly coact with the corresponding rounded portion of the end wall 32 of the member B, as the cars pass over a curved track.

In draft action, it is evident that the member A will be pulled outwardly from the car end by chain 27, the outer ends of the springs C being held by the member B, which in turn is held by the bolts 20 and 36, thus compressing the springs C. The limit of outward movement of the member A is reached when the front ends of the webs 24 engage the inner side of the wall 32 of the member B, the clearance between the webs 24 and the wall 32 being sufficient to allow the springs to come into proper play. Thus the webs 24 act as a limiting stop serving to avoid injury to the springs by preventing them from being driven solid under an unusually heavy shock, whether under pulling strains or in buff.

In a buffing action, the member B is forced inwardly by contact with the buffing plates 45 of the adjacent car, the inner ends of the springs C, in this instance, being held by the member A which is in abutment with the end sill or end portions of the flooring 10.

Referring next to the embodiment of the invention illustrated in Figures 4 and 5, 110 designates the flooring of each mine car and 111' the end wall. Each car is provided with a draw-bar 112, extending full length of the car, and identical in all respects with that shown in Figures 1 to 3 except at the closed end, and the gate end of the car is provided with a pair of buffing plates 145 in all respects similar to the corresponding parts illustrated in Figures 1 to 3, inclusive.

The closed end of each car is provided with an auxiliary draw-bar 113 substantially similar to the bar 13 previously described, the only difference between the bars 112 and 113 and the bars 12 and 13 being that the former are perforated to accommodate the bolt 120 so that the bolt is positively held against movement relative thereto.

The shock absorbing mechanism proper, as shown in Figures 4 and 5, comprises a housing A'; a follower B'; a pair of spring

caps C'; a pair of spring followers D'; a which in turn are held by the flanges theveof pair of springs E'; and a bearing plate F'.

The housing A' is in the form of a casting having spaced top and bottom walls 150 and 151, front wall 152 and vertically extending webs 153 connecting the top and bottom walls. The top and bottom walls straddle the end portion of the flooring 110 and the bars 112 and 113, and the webs 153 abut the inner side faces of the projecting portions of the flooring 110, the flooring being cut away at 116 to accommodate the shock absorbing mechanism. At either side of the center line, the housing is provided with a boss 154 having an opening adapted to slidely receive one of the spring follower caps C'.

The member B' is in the form of a bar extending horizontally and provided at each end with a recess 155 adapted to pivotally accommodate a boss 156 on the corresponding spring follower D', the spring followers D' being thus mounted for pivotal movement. Centrally, the member B' is formed with an extension 157 provided with a vertically disposed slot 158 adapted to slidely receive the bolt 120, thereby permitting limited movement of the member B' relatively to the housing A' and outwardly from the car. The member B' is connected to the chain 127 by means of a shackle 128 pivotally secured to the extension 157 by means of a vertically arranged pin 160. The rear face of the member B' is rounded to a large radius as indicated at 161 so that the same may have rocking movement on the flat bearing plate F' interposed between the same and the end of the flooring 110.

The spring caps C' are of like construction, each being in the form of a hollow casting provided with a laterally projecting peripheral flange 162 at the rear end thereof adapted to engage with a shoulder 163 at the inner end of the corresponding boss 154, thereby limiting the outward movement of the spring cap. The springs E' are interposed under initial compression when in normal position as shown, between the spring followers D' and the caps C', sufficient clearance being left between the spring followers D' and the flanged inner ends of the caps to permit the springs to come into play. Outward movement of the member B' is limited by engagement of the spring followers D' with the inner ends of the spring caps C', these parts acting as a limiting stop serving to prevent damage to the springs through being driven solid.

In draft action, the operation of the device just described is substantially the same as the operation of the device described in connection with Figures 1, 2 and 3, the member B' being pulled outwardly from the end of the car by the chain 127, the outer ends of the springs E' being held by the caps C',

which in turn are held by the flanges theveof engaging the shoulders at the inner ends of the bosses 154. The limit of outward movement of the member B' is reached when the outer faces of the spring followers D' engage the flanges 162 of the caps C'.

In a buffing action, the caps C' are forced inwardly by contact with the plates 145 of the adjacent car, movement of the inner ends of the spring C'-C', in this instance, being resisted by the spring followers D', movement of which in turn is opposed by the member B' abutting the wear plate F'.

In the form of the device shown in Figures 4 and 5, it will be noted that I obtain a balanced resistance in both buff and draft regardless of the forces being applied parallel to or at an angle to the center line of the car, due to the rocking draft member and the spring caps D' which are rockably mounted thereon. Furthermore, even though a buffing force is applied initially solely to one of the spring caps C', nevertheless, I will obtain approximately the resistance of both springs, due to the bar B' rocking so as to shift the fulcruming point, decreasing the lever arm on that side to which the pressure is applied and increasing the lever arm between the fulcruming point and the other spring.

I have herein shown and described what I now consider the preferred manner of carrying out the invention, but the same is merely illustrative, and I contemplate all changes and modifications which come within the scope of the claims appended hereto.

I claim:

1. In a car, the combination with a drawbar fixed to one end of the car and projecting outwardly therefrom, said drawbar being slotted; of a buffing member; a pin fixed to said buffing member and working in the slot of said drawbar; a draft member adapted to abut the end of the car, said buffing and draft members being movable relatively toward and from each other; cushioning means interposed between said buffing and draft members; and means for detachably connecting the draft member to an adjacent car.

2. In a mine car, the combination with a main draw-bar; of an auxiliary drawbar; said main and auxiliary drawbars being fixed to the car and projecting beyond the end of the same; a draft member working between said main and auxiliary drawbars; a buffing member straddling said main and auxiliary drawbars; a guide pin for connecting said buffing member and draft member for relative movement to each other and relative to the main and auxiliary drawbars; and a spring resistance interposed between said buffing and draft members.

3. In a car, the combination with the end structure of said car having a floor provided

- with a recess; of a draft member arranged in said recess; a buffing member adapted to be actuated by direct contact with an adjacent car, said buffing member and said draft member being connected to said car for relative movement toward and from each other, said draft member being provided with a pivoted coupling element adapted in inoperative position to be disposed within the outermost limits of said buffing and draft members, and extending outwardly of the latter when in operative position; and cushioning means interposed between said members.
- 15 4. In a car, the combination with a draft member mounted at one end of the car and held against movement inwardly of the car, said draft member extending to both sides of the center line of the car and having a central pivotal slotted connection with a vertically extending pin carried by said car, to permit movement of said draft member in a substantially horizontal plane; of a buffing member adapted to be actuated by direct contact with an adjacent car, said member being connected at its opposite ends to said car to hold said buffing member against outward movement and permit limited inward movement thereof; and cushioning means interposed between said draft and buffing members at opposite sides of said pivotal connection, said draft member being provided with a central coupling ele-
- 50 ment adapted to detachably connect said draft member to an adjacent car.
5. In a car, the combination with a draft member; of a buffing means adapted to be actuated by contact with an adjacent car; cushioning means interposed between said draft member and said buffing member; and means for equalizing resistance on said cushioning means with respect to said buffing and draft members during both buff and draft when the actuating force is applied thereto at an angle to the normal movement of the draft and buffing members.
6. In a car, the combination with a draft member mounted at one end of the car and having an engaging portion adapted to abut said car to limit inward movement thereof, said draft member being pivotally connected to said car to permit limited outward movement thereof, said engaging portion being curved; buffing means extending to both sides of the center line of the car, and including spaced caps movable inwardly with respect to said buffing means and limited against outward movement; followers rockably carried by the opposite ends of said draft member; and cushioning means interposed between said caps and said followers.

In witness that I claim the foregoing I have hereunto subscribed my name this 21st day of September, 1923.

STACY B. HASELTINE.
